Gifford & Bell ATTORNEYS

UNITED STATES PATENT OFFICE.

JAMES KEMNAL, OF LONDON, ENGLAND, ASSIGNOR, BY MESNE ASSIGNMENTS, TO THE BABCOCK & WILCOX COMPANY, OF BAYONNE, NEW JERSEY, A CORPORATION OF NEW JERSEY.

STEAM-BOILER INSTALLATION.

Application filed December 27, 1917, Serial No. 209,049, and in Great Britain August 17, 1917. Renewed March 8, 1924.

This invention relates to an improved steam boiler installation comprising a steam generator or boiler proper, a superheater or superheaters, and a re-heater for the steam.

5 A novel feature of the invention is the disposition of the re-heater above the superheater; the generator, superheater and re-heater being in superposed relationship.

The function of such re-heater is to effect 10 re-heating to a higher temperature than that due to its pressure of the steam in its passage from one stage to another stage of a steam turbine or from one cylinder to another cylinder of a reciprocating engine, or 15 for any purpose for which re-heated steam is desirable.

The invention further provides an adjustable baffling arrangement or damper whereby 20 it is rendered practicable to pass the gaseous products of combustion directly over the superheater tubes without their passing over the tubes of the re-heater or to regulate the passage of gases over the tubes of the superheater or the re-heater to any desired extent 25 with a view to regulation of the degree of superheating action effected in the superheater or the re-heater.

Yet another feature consists in the provision of an air heater.

30 In the accompanying drawings, Fig. 1 is a vertical sectional elevation of an illustrative form of the invention; Fig. 2 is a section on line 2—2 of Fig. 1; Fig. 3 is a section on line 3—3 of Fig. 2; Fig. 4 is a partial section 35 on line 4—4 of Fig. 3 and Fig. 5 is an enlarged fragment of Fig. 1, showing the relation between the stationary and movable baffles.

Referring to the drawings, it will be seen 40 that the generator proper, indicated generally by the reference numeral 1, is of the well known Babcock & Wilcox type, whether stationary or marine, the generator being herein shown as fired by a chain-grate-stoker, but it may be fired with oil or gas, or in any other manner.

Above the generator proper is or are the 45 superheater or superheaters 2 which may be of any known or suitable construction, but 50 preferably of the U-tube type.

Above the superheater or superheaters 2, in turn, is the re-heater comprising, in the instance shown, cylindrical vessels 3 having

suitable inlets and outlets, joined by tubes 4; the arrangement being such that the steam 55 may flow directly from one vessel 3 to the other through the tubes 4.

The tubes 4 are curved, as shown, to facilitate expansion.

5 denotes a baffle or damper which is 60 mounted for vertical sliding movement, being operable, for example, by means of gearing, the said baffle serving to control the passage of gaseous products of combustion over the superheater and re-heater tubes. The 65 baffle 5 engages a stationary baffle *a* at the point *b*.

On reference to the drawing it will be seen that when the baffle 5 is raised to its highest position a clear passage is open for 70 the gases to pass directly over the superheater tubes without their passing over the re-heater tubes. It will also be apparent that, according to the extent to which the baffle is raised, a greater or less area open 75 to the passage of gases in among the superheater tubes will be presented, whereby the re-heating action effected in the re-heater may be conveniently regulated. It will be noted that there is a casing 11 of smaller 80 dimensions than the outer boiler casing which casing 11 encloses the superheater and re-heater, and that there is provided a passage-way 12 extending over the front of the casing 11 and thence over its top and 85 through which the products of combustion pass before reaching the air heater.

The air heater comprises a chamber located adjacent to the generator and containing vertical tubes 6 fitted to tube-plates 7, 90 8, the arrangement being such that the gaseous products of combustion pass downwards through the tubes 6 while the air entering at 9 flows around the outside of tubes 6, being baffled by means of baffles 10. 95

The setting is provided at either side with a casing 20 spaced from the inner walls of the setting to provide air passages 21 at either side of the setting. The heated air from the air heater tubes 6 enters a horizontal duct 22 and from thence flows through openings 23, (one of which is at each end of duct 22) into the upper part of the passages 21. Openings 24 lead from passages 21 to the stoker in the furnace, and the 100 heated air flows downward through pas- 105

sages 21 to the openings 24 and into the stoker. In order to compel the air to flow along the sides of the casing 11, a vertical baffle or partition 25, and a horizontal baffle 5 or partition 26 extend across each passage 21 between the outer and inner walls of the setting, so that the air flows, as shown by dotted arrows in Fig. 3, first upwardly and over the top of baffle 25, and then downward to the openings 24.

10 The heated air aids in the combustion and economy of the boiler. Moreover, by having the air heated before it passes over the furnace wall, which is built of brick or tile, as usual, an advantage is gained over the similar use of unheated air, because any heated air percolating through the brick-work, will not reduce the efficiency to the same extent as unheated air, and such heated 15 air more readily combines with any unburned gases near the furnace walls. Furthermore, by using heated air, there is less difference in temperature between the inside and the outside of the brickwork, and 20 correspondingly less tendency for the wall to be injured by unequal expansion of the two sides.

25 In the drawings the path of the gaseous products of combustion is indicated by full-line arrows; the path of the air being indicated by dotted line arrows.

30 By causing the gases to flow downwardly through the air heater, any moisture formed within the tubes because of the condensation 35 of vapors in the gases will be swept downwardly with the gases and thus obviate any difficulty due to the moisture, when formed, which is ordinarily of a highly corrosive 40 nature, from running back over the air heater, as would be the case were the gases caused to pass upwardly through the air heater.

45 What I claim is:—

1. The combination with a steam generator, of a superheater and a steam reheat 50 er arranged to be contacted with successively by the waste gases, and baffling arranged to direct the gases over a portion of the heating surface of the boiler, thence over a portion of the superheater, thence over a portion of the reheat and thence back in succession over the reheat, superheater and boiler heating surface.

55 2. The combination with a steam generator and a superheater, of a steam reheat 60 er above the generator, a casing enclosing the reheat, and means for passing the products of combustion over said superheater and reheat and around said casing after leaving the generator.

65 3. The combination with a steam generator and a superheater, of a steam reheat 70 er above the generator, a casing enclosing the reheat, means for passing the products of combustion around said casing after leaving

75 ing the boiler, an air heater, and means for passing the hot air from the air heater around the portions of the casing for the steam reheat.

80 4. The combination with a steam generator, of a superheater and a steam reheat 75 er arranged to be contacted with successively by the waste gases, and movable baffling arranged to direct the gases in succession over a portion of the heating surface of the boiler, a portion of the superheater and a portion of the reheat, thence back in succession over the reheat, superheater and boiler heating surfaces, said baffling being arranged to divert gases from the reheat.

85 5. A steam boiler and its setting, a heat-transfer device, a casing enclosing the same spaced from the walls of said setting, an air heater, means for directing furnace gases over said heat-transfer device and thence 90 between the walls of said setting and said casing to said air heater, and means for directing the air from said air heater between the walls of said setting and said casing to the boiler furnace.

95 6. A steam boiler and its setting, a heat-transfer device, a casing enclosing the same spaced from the walls of said setting, an air heater comprising vertically-arranged heating tubes, means for directing furnace gases over said heat-transfer device and thence 100 upwardly between the walls of said setting and said casing and downwardly through the tubes of said air heater, and means for directing air upwardly over said air heater and thence downwardly between the walls of 105 said setting and said casing to the boiler furnace.

110 7. A steam generator and its setting, a heat-transfer device located above said generator, an air heater located at the side of said generator and said heat-transfer device, a casing enclosing said heat-transfer device, and means for directing furnace gases over said generator and said heat-transfer device and thence between the walls of said setting and said casing to said air heater.

115 8. A steam generator and its setting, said generator comprising horizontally-arranged boiler tubes, a heat-transfer device located above said generator, an air heater located at the side of said generator and said heat-transfer device, a casing open at its bottom enclosing said heat-transfer device, and means for directing furnace gases across said boiler tubes over said heat-transfer device, thence over said boiler tubes and thence between the walls of said setting and said casing to said air heater.

120 9. A steam generator and its setting, said generator comprising horizontally-arranged boiler tubes, a heat-transfer device located above said generator, an air heater located at the side of said generator and said heat-transfer device, a casing open at its bottom 125

130

- enclosing said heat-transfer device, means for directing furnace gases across said boiler tubes over said heat-transfer device, thence over said boiler tubes and thence between the walls of said setting and said casing to said air heater, and means for directing the heated air from said air heater between the walls of said setting and said casing to the boiler furnace.
10. 10. A steam generator and its setting, said generator comprising horizontally-arranged boiler tubes, a heat-transfer device located above said generator, an air heater located at the side of said generator and said heat-transfer device, a casing open at its bottom enclosing said heat-transfer device, means for directing furnace gases across said boiler tubes, thence over said heat-transfer device, thence over said boiler tubes and thence upwardly between the walls of said setting and said casing to said air heater, and means for directing air upwardly over said air heater and thence downwardly between the walls of said setting and said casing to said boiler furnace.
11. In combination, a setting, a furnace to supply heated gases to said setting, means in said setting to absorb heat from the furnace gases, a casing enclosing said setting, a combustion air heater, means for directing waste furnace gases from said heat-absorbing means between the walls of said setting and said casing to said air heater, and means for conducting air through said air heater and also between the walls of said setting and said casing to said furnace, whereby radiation losses from said heat-absorbing means is minimized.
12. In combination, a setting, a furnace to supply heated gases to said setting, means in said setting to absorb heat from the furnace gases, a casing enclosing said setting, a combustion air heater having vertically-arranged heating tubes, means for directing waste furnace gases from said heat-absorbing means upwardly between the walls of said setting and said casing and downwardly through
- the tubes of said air heater, and means for conducting air upwardly through said air heater and also downwardly between the walls of said setting and said casing to said furnace, whereby radiation losses from said heat-absorbing means is minimized.
13. In combination, a steam generator and a heat transfer device each contacted by hot gases from the generator furnace, a flue having one end closed and a gas inlet and a gas outlet at a portion of the flue remote from said closed end, said heat transfer device having tubes arranged in rows in said flue between the gas inlet and the closed end, and a baffle between a pair of said rows and movable between said rows toward and away from said closed end and at one side of said inlet.
14. In combination, a steam generator and a heat transfer device each contacted by hot gases from the generator furnace, a flue having one end closed and a gas inlet and a gas outlet side by side at the end of the flue opposite said closed end, said heat transfer device having tubes arranged in rows in said flue between the gas inlet and the closed end, and a baffle between a pair of said rows and movable between said rows toward and away from said closed end and in a plane between said inlet and said outlet.
15. In combination, a steam generator and a heat transfer device each contacted by hot gases from the generator furnace, a flue having one end closed and a gas inlet and a gas outlet at a portion of the flue remote from said closed end, said heat transfer device having tubes arranged in rows in said flue between the gas inlet and the closed end, and a baffle between a pair of said rows and movable between said rows from a position with one end closely adjacent said closed end to a position with its other end closely adjacent said inlet and outlet.

In testimony whereof I have signed my name to this specification.

JAMES KEMNAL.
